UNITED STATES PATENT OFFICE

JOHN DOLAN, OF DAYTON, OHIO

LIFTING MECHANISM

Application filed October 17, 1927. Serial No. 226,600.

This invention relates to lifting mechanisms and is designed more particularly for use in lifting jacks.

One object of the invention is to provide a lifting mechanism having a plurality of relatively movable lifting members with a means for controlling the relative movements of said members.

A further object of the invention is to provide such a device in which both lifting members may be provided with teeth of a width substantially equal to the width of the outer lifting member.

A further object of the invention is to provide such a lifting mechanism having telescoping lifting members so constructed and arranged as to provide a lifting element which will be simple in its construction and which will have great strength and durability.

A further object of the invention is to provide such a lifting mechanism with means whereby the lifting element may be operated at different speeds, at the will of the operator.

Other objects of the invention will appear as the mechanism is described in detail.

In the accompanying drawings Fig. 1 is a side elevation, partly in section, of a lifting jack embodying my invention; Fig. 2 is a side elevation of the upper portion of the jack, partly in elevation, and partly in section, showing the lifting members in extended positions; Fig. 3 is a sectional view taken on the line 3-3 of Fig. 1; Fig. 4 is a sectional view taken on the line 4-4 of Fig. 1; Fig. 5 is a sectional view taken on the line 5-5 of Fig. 1; Fig. 6 is a plan view of the jack, partly in section; Fig. 7 is a detail view of the locking pawl; and Fig. 8 is a vertical section taken through the lifting members and showing the inner member in its elevated position.

In these drawings I have illustrated one embodiment of my invention and have shown the same as applied to an automobile jack but it will be understood that the mechanism may take various forms and may be utilized with lifting mechanisms of various kinds without departing from the spirit of the invention.

In that embodiment here shown the jack

comprises a base 10 having rigidly secured thereto an upwardly extending hollow standard 11. Slidably mounted in this standard is a lifting element which preferably consists of two relatively movable telescopic members. 55 Preferably the outer lifting member is substantially rectangular in form, as shown at 12, and fits snugly between the side walls of the standard 11. This outer member is provided with a longitudinally extending guideway which opens through one of the side walls thereof. This outer lifting member may be formed in various ways but I prefer to utilize a bar of metal of the proper dimensions and to provide the same with a longitudinal bore 60 arranged substantially centrally thereof, as shown at 13, and to then cut away one wall of the member, in the present instance the rear wall, to provide a vertical opening 14. If desired, the edges 15 of this outer member, 65 on opposite sides of the opening 14, may be beveled, or flared outwardly. The outer lifting member 12 is provided on that side opposite the opening 14 with teeth 16 extending for the full width thereof. Slidably mounted in the guideway or bore 13 of the outer member 70 is a cylindrical or body portion 17 of an inner lifting member, this cylindrical portion having a sliding fit in the bore of the outer member. Rigidly secured to the body 75 portion 17 of the inner member is a rack portion 18. As here shown, this rack bar is of a width substantially equal to the width of the outer member 12, has on its outer face teeth 19 extending for the full width thereof and 80 has on its inner side a longitudinally extending tongue or rib 20 which extends through the opening in the rear wall of the outer lifting member and is rigidly secured 85 in a groove 21 in the body portion 17 of the inner member. The tongue 20 and the groove 21 are preferably dove-tailed and a pin 22 extending through the same and through the adjacent portions of the part 17 serves to 90 rigidly connect the two parts of the inner lifting member one to the other. The laterally extending portions or flanges of the rack 18 preferably bear against and have sliding movement on the edges 15 for the outer lifting member. In this manner I am able to 95 100

provide both the inner and outer lifting members with rack teeth of a transverse length equal to the width of the outer lifting member, thus providing those teeth with a large degree of strength. The construction of the lifting element is such that the parts may be easily manufactured and assembled and when assembled will be of a very strong durable character.

It will be noted that the teeth of the two lifting members are arranged on the opposite sides of the lifting element as a whole and the two lifting members are operated by pinions 23 and 24, respectively, which are mounted on shafts 25 and 26 journaled in suitable bearings on the standard 11. These pinions are arranged near the upper end of the standard and the front and rear walls of the standard are cut away to provide openings through which the pinions extend to enable them to mesh with the respective rack teeth. The pinions may be operated in any suitable manner but, in the present instance, they are rotated simultaneously from a common source of power and to this end intermeshing gears 27 and 28, of the same diameter, are mounted on the shafts 25 and 26, and secured to one of these shafts, in the present instance the shaft 25, is a worm wheel 29 constituting a driving element for the rack operating pinions and which is driven in a manner hereinafter described. Preferably one of the lifting members is elevated to the upper limit of its movement before the other lifting member is actuated. In the present instance, the inner lifting member is first operated and the outer lifting member is so controlled that it will have no vertical movement until the inner lifting member has completed its upward movement with relation thereto, and will then be actuated, the inner member being then locked to the outer member to retain it in its extended position with relation thereto. As has been stated, the actuating pinions 23 and 24 are rotated simultaneously and to prevent the movement of the outer member during the initial movement of the inner member the teeth 16 of the outer member terminate just below the pinion 24 so that when the outer member is in its lowermost position the pinion 24 can rotate without engaging the teeth. Consequently when the actuating pinions are rotated the inner member only will be elevated. Means are provided for moving the outer lifting member upwardly, after the inner member has reached its limit of movement with relation thereto, to cause the teeth 16 to be moved into operative relation to the pinion 24. This may be accomplished in various ways but, as here shown, the body 17 of the inner member has a second vertical groove 30, the lower end of which forms a stop, as shown at 31. Rigidly secured to the outer member, near the upper end there-

of, and extending into the groove 30, is a projection, such as a block 32, so arranged that as the inner member reaches the upper limit of its movement with relation to the outer member the stop 31 will engage the block 32 and the further movement of the inner member by its pinion 23 will cause the outer member to move with it, thereby carrying the teeth 16 into mesh with the pinion 24. After the pinion 24 is in mesh with the teeth 16 the teeth 19 move out of mesh with the pinion 23, and the two lifting members are moved upwardly simultaneously by the pinion 24. It will be obvious that the groove 30 may be formed in either member and the projection carried by the other member.

Any suitable means may be provided for locking the inner member in its extended position with relation to the outer member but it is important that this mechanism should be positively controlled to prevent the accidental release of the inner member and the dropping of the load. As here shown, the locking means comprises a pawl 33 rigidly secured to a shaft 34 journaled in suitable bearings in an enlarged upper portion or collar 35 carried by the outer member, this collar being recessed to receive the pawl 33 and to permit the same to be moved into and out of locking engagement with the teeth 19 of the rack bar 18. Rigidly secured to the shaft 34, at one side of the collar 35, is an actuating arm comprising an upper portion 36 and a lower portion 37. The upper portion of the arm is acted upon by a spring 38^a which tends to rock the shaft 34 in a direction to cause the pawl 33 to engage the teeth 19. The lower portion 37 of the pawl actuating arm is preferably curved and may, if desired, be tapered as shown in Fig. 1. Rigidly secured to the standard 11 are two projections or studs 38 and 39 which are so arranged that when the outer lifting member is in its lowermost position the portion 37 of the actuating arm will lie between these studs and the lower end thereof will extend beneath the stud 38. When an upward movement is imparted to the outer lifting member the arm 37 will ride over the stud 38, thus causing the shaft 34 to be rocked in a direction to move the pawl into locking position, in which position it will be held by the spring 38^a. When the outer lifting member moves downwardly and approaches its lowermost position the outer edge of the part 37 of the actuating arm will engage and ride over the stud 39, thus rocking the shaft 34 to move the pawl out of engagement with the teeth of the inner lifting member and releasing that member so that it can move downwardly with relation to the outer member. While the spring 38^a would ordinarily hold the pawl in its operative position I prefer to provide a positive lock for that pawl and I have therefore provided the pawl 130

actuating arm with a forwardly extending finger 40. Cooperating with this finger is a locking member 41 pivotally mounted at its upper end on the collar 35 of the outer lifting member. This locking member has a projection or lug 42 extending rearwardly from the edge thereof and adapted to engage over the forward end of the finger 40 of the pawl actuating arm when the pawl is in its locking position. A spring acts on the locking member 41 to move the same into and hold it in its locking position and, in the present instance, the spring 38^a is connected with the arm 41 and acts both on that arm and on the pawl actuating arm. The lower end of the locking arm 41 is beveled and arranged to engage a projection or stud 43 on the standard 11 when the outer lifting member approaches its lowermost position, thereby causing the locking member to be moved forwardly to disengage the projection 42 from the finger 40 and release the pawl actuating arm for movement by the stud 39, the arrangement of the studs 43 and 39 being such that the arm 41 will be operated before the arm 37 engages the stud 39. When the outer lifting member moves upwardly the arm 42 will move out of engagement with the stud 43 after the arm 37 has been actuated by the stud 38 to move the pawl 33 to locking position, thus permitting the projection 42 of the arm 41 to operatively engage the finger 40.

To prevent the possibility of the outer lifting member being dragged upwardly by the inner lifting member, and thus causing its teeth to engage the cooperating pinion before the inner member has completed its movement, I have provided a lock which will positively prevent the upward movement of the outer member but which will be automatically released before the inner member reaches the upper limit of its movement with relation to the outer member. As shown in Fig. 1, this locking member comprises an arm 44 pivotally mounted on the outer lifting member and having a nose 45 to engage beneath a flange 46 at the upper edge of the standard 11. A spring 47 holds the locking arm normally in its operative position. Extending rearwardly from the arm 44 is a finger 48 arranged to be engaged by the laterally extending portion 49 of a rod 50, which extends through a slot in the side wall of the outer member and has a vertical portion slidably mounted in a guideway in the projection 32 and extending below the projection so that it will be engaged by the bottom of that groove, the stop 31, just before that stop engages the projection, thus causing the lock to be moved to its inoperative position before the inner member is connected with the outer member.

The worm wheel 29 meshes with a worm 51 carried by a shaft 52 journaled in bearings

53 and 54 on the standard 11, the bearing 54 being formed, in the present instance, in one wall of a gear casing 55. The worm may be actuated in any suitable manner but I prefer to provide an actuating mechanism therefor of such a character that the worm, and consequently the lifting element, may be operated at different speeds at the will of the operator. To this end I have here shown a second shaft 56 mounted in a bearing 57 in the forward wall of the gear casing 55 and adapted to be connected with a suitable operating device, such as a crank, and interposed between the shaft 56 and the worm shaft 52 is multiplying gearing which may be connected with or disconnected from the shaft 56 at will. As here shown, the forward end of the shaft 52 is hollow and the rear end of the shaft 56 extends into and is rotatably and slidably mounted in the hollow end portion 85 of the shaft 52. Rigidly secured to the shaft 52 is a pinion 58 which meshes with a gear 59 on a shaft 60, also journaled in the gear casing. A pinion 61 rigidly secured to the shaft 60 meshes with a gear 62 which is loosely mounted on the shaft 56. Rigidly secured to the gears 58 and 62 are clutch members 63 and 64, the adjacent ends of which are spaced apart. Rigidly secured to the shaft 56 is a clutch member 65 which is adapted to operatively engage either of the clutch members 63 and 64. A spring 66 in the hollow shaft 52 acts on the end of the shaft 56 to move that shaft outwardly and thus hold the clutch member 65 normally in operative engagement with the clutch member 64. With the clutch in this position the rotation of the shaft 56 will be transmitted to the shaft 52 through the multiplying gearing and the worm and lifting element will be operated at a high speed. By pressing inwardly on the shaft 56 the clutch member 65 may be disconnected from the clutch member 64 and connected with the clutch member 63, thus establishing a direct connection between the shaft 56 and the shaft 52 and causing the latter to rotate at the same speed as the shaft 56, the gear train running idle during this direct connection. It will be apparent, therefore, that after the jack has been placed in position the lifting element may be operated at high speed to run the same quickly up into engagement with the work and by then shifting the clutch it may be operated at a lower speed to lift the load. Likewise the lifting element may be lowered either at high speed or at low speed. The clutch members may be of any suitable character but in order to prevent the accidental disengagement of the clutches I have so constructed the members that they will be locked in engagement one with the other. To this end the slots 67 in the clutch members 63 and 64 are T-shaped, and the teeth or lugs 68 on the clutch member 65 are of such a shape that they will pass

through the narrow portions of the T-shaped slots and when the shaft 56 is rotated will be moved behind the shoulders at those sides of the slots toward which the shaft is rotated. Thus the clutch member 65 will be held in engagement with the other clutch member until the shaft is rotated in a reverse direction to bring the teeth 68 into line with the narrow portions of the T-shaped slots.

10 While I have shown and described one embodiment of my invention I do not desire to be limited to the details thereof as various modifications may occur to a person skilled in the art.

15 Having now fully described my invention, what I claim as new and desire to secure by Letters Patent, is:

1. In a lifting mechanism, a hollow standard, an outer lifting member mounted for vertical movement in said standard, having teeth on one side thereof and having a longitudinal guideway opening through the other side thereof, an inner lifting member slidably mounted in said guideway and having a part extending beyond said guideway and overlapping the edges of said outer member at the sides of said guideway, said part of said inner lifting member having teeth on the outer side thereof, separate pinions to engage the teeth on the respective lifting members, and means to actuate said pinions.

2. In a lifting mechanism, a hollow standard, an outer lifting member mounted in said standard for vertical movement, having teeth on one side thereof, having a longitudinal guideway therein, and having an opening through another side thereof, said opening being of a width less than the width of said guideway, an inner lifting member having a part slidably mounted in said guideway, and a part extending through said longitudinal opening and having flanges which overlap the edges of said outer member on the respective sides of said opening, said flanged part having teeth on the outer side thereof, pinions to engage the teeth on the respective members, and means for actuating said pinions.

3. In a lifting mechanism, a hollow standard, an outer lifting member mounted in said standard for vertical movement, having teeth on one side thereof and having a longitudinal cylindrical bore and also having a longitudinal opening through another side thereof, an inner lifting member comprising a cylindrical part slidably mounted in the bore of the first mentioned member, a rack bar of a width substantially equal to the width of said outer member, having teeth on its outer side and having a part extending through said opening in said outer lifting member and rigidly secured to the first mentioned part of said inner member, said standard having openings in the walls thereof near its upper end, pinions rotatably mounted on

said standard and extending through said openings to engage the teeth on the respective lifting members, and means for actuating said pinions.

4. In a lifting mechanism, a hollow standard, an outer lifting member mounted in said standard for vertical movement, having teeth on one side thereof and having a longitudinal cylindrical bore and also having a longitudinal opening through another side thereof, an inner lifting member comprising a cylindrical part slidably mounted in the bore of the first mentioned member, a rack bar of a width substantially equal to the width of said outer member, having teeth on its outer side and having a part extending through said opening in said outer lifting member and rigidly secured to the first mentioned part of said inner member, said cylindrical portion of said inner member having a longitudinal groove therein and a stop at the lower end of said groove, and said outer member having a part projecting into said groove and adapted to be engaged by said stop to impart initial movement to said outer member, pinions to engage the teeth on the respective lifting members, the pinion for the outer lifting member being so arranged that it will be out of engagement with the teeth of that lifting member when the latter is in its lowermost position, and means for actuating said pinions.

5. In a lifting mechanism, a hollow standard, an outer lifting member mounted in said standard for vertical movement, an inner lifting member mounted within said outer lifting member, means for first moving said inner lifting member to its uppermost position with relation to said outer lifting member and for then imparting movement to said outer lifting member, a locking member carried by said outer lifting member and movable into and out of locking engagement with the inner lifting member, an actuating arm connected with said locking member and having a curved lower portion, and parts carried by said standard to engage said curved portion of said arm and move said locking member into locking position when said outer lifting member is moved upwardly and to engage said curved portion of said actuating arm and move said locking member into its inoperative position, when said outer lifting member approaches the lower limit of its movement.

6. In a lifting mechanism, a hollow standard, an outer lifting member mounted within said standard for vertical movement and having teeth on one side thereof, an inner lifting member mounted within said outer lifting member for vertical movement with relation thereto and having teeth on one side thereof, pinions carried by said standard to engage the teeth of the respective lifting members, the pinion for the outer lift-

- ing member being so arranged that it will be out of engagement with the teeth thereof when said outer lifting member is in its lowermost position, means for moving the teeth of said outer lifting member into engagement with said pinion when said inner lifting member has completed its movement with relation to said outer lifting member, a pawl mounted on said outer lifting member for movement into and out of engagement with the teeth of said inner lifting member, an actuating arm rigidly connected with said pawl and having a curved lower end, pins carried by said standard and so arranged that when said outer lifting member is moved upwardly from its lowermost position said actuating arm will be moved in a direction to move the pawl into engagement with said teeth, and when said outer lifting member approaches the lower limit of its movement said actuating arm will be moved in a direction to move said pawl out of engagement with said teeth.
7. In a lifting mechanism, a hollow standard, an outer lifting member mounted within said standard for vertical movement and having teeth on one side thereof, an inner lifting member mounted within said outer lifting member for vertical movement with relation thereto and having teeth on one side thereof, pinions carried by said standard to engage the teeth of the respective lifting members, the pinion for the outer lifting member being so arranged that it will be out of engagement with the teeth thereof when said outer lifting member is in its lowermost position, means for moving the teeth of said outer lifting member into engagement with said pinion when said inner lifting member has completed its movement with relation to said outer lifting member, a pawl mounted on said outer lifting member for movement into and out of engagement with the teeth of said inner lifting member, an actuating arm rigidly connected with said pawl and having a curved lower end, pins carried by said standard and so arranged that when said outer lifting member is moved upwardly from its lowermost position, said actuating arm will be moved in a direction to move the pawl into engagement with said teeth and when said outer lifting member approaches the lower limit of its movement said actuating arm will be moved in a direction to move said pawl out of engagement with said teeth, a locking member carried by said outer lifting member and arranged to engage a part carried by said actuating arm and retain said locking pawl in engagement with said teeth, and means for moving said locking member into an inoperative position as said outer lifting member approaches the lower limit of its movement.
8. In a lifting mechanism, a hollow stand-
- ard, an outer lifting member mounted in said standard for vertical movement, an inner lifting member mounted in said outer lifting member for vertical movement with relation thereto, means for moving said inner lifting member to the limit of its movement with relation to said outer lifting member and then imparting movement to said outer lifting member, a locking member carried by said outer lifting member and movable into and out of a position to lock said inner lifting member in its extended position with relation to said outer lifting member, an actuating arm connected with said locking member, means carried by said standard to move said actuating arm in one direction when upward movement is imparted to said outer lifting member, and to move said actuating arm in the other direction as said outer lifting member approaches the lower limit of its movement, a finger secured to said actuating arm, an arm movably mounted on said outer lifting member and having a part adapted to engage said finger to retain said locking member in its locking position, and a part carried by said standard to move said arm out of engagement with said finger as said outer lifting member approaches its lowermost position.
9. In a lifting mechanism, a standard, a toothed lifting member mounted for vertical movement with relation to said standard, a pinion to actuate said lifting member, means for operating said pinion at different speeds comprising a shaft operatively connected with said pinion, a second shaft, multiplying gearing connected with one of said shafts, and means for connecting said gearing with the other shaft or for connecting said second shaft directly with the first mentioned shaft.
10. In a lifting mechanism, a standard, a toothed lifting member mounted for vertical movement with relation to said standard, a pinion to actuate said lifting member, means for operating said pinion at different speeds comprising a shaft operatively connected with said pinion, a second shaft arranged in axial alinement with the first mentioned shaft and capable of both axial and rotatory movement with relation thereto, a gear rigidly secured to the first mentioned shaft, a second gear rotatably mounted on the last mentioned shaft, intermediate gears connecting the first mentioned gears, and means controlled by the axial movement of said last mentioned shaft to connect the same either directly with the first mentioned shaft or with that gear which is loosely mounted on the last mentioned shaft.
11. In a lifting mechanism, a standard, a toothed lifting member mounted for vertical movement with relation to said standard, a pinion to actuate said lifting member, means for operating said pinion at different speeds

comprising a shaft operatively connected with said pinion, a second shaft arranged in axial alinement with the first mentioned shaft and capable of both axial and rotatory movement with relation thereto, a gear rigidly secured to the first mentioned shaft, a second gear rotatably mounted on the last mentioned shaft, intermediate gears connecting the first mentioned gears, and clutch members secured to the two first mentioned gears, a clutch member rigidly secured to the last mentioned shaft and adapted to be moved into operative engagement with either of the first mentioned clutch members by the axial movement of said shaft.

12. In a lifting mechanism, a standard, a toothed lifting member mounted for vertical movement with relation to said standard, a pinion to actuate said lifting member, means for operating said pinion at different speeds comprising a shaft operatively connected with said pinion, a second shaft arranged in axial alinement with the first mentioned shaft and capable of both axial and rotatory movement with relation thereto, a gear rigidly secured to the first mentioned shaft, a second gear rotatably mounted on the last mentioned shaft, intermediate gears connecting the first mentioned gears, clutch members secured to the two first mentioned gears, a clutch member rigidly secured to the last mentioned shaft and adapted to be moved into operative engagement with either of the first mentioned clutch members by the axial movement of said shaft, and a spring tending to hold the last mentioned clutch member in operative engagement with that clutch member which is carried by the gear loosely mounted on the last mentioned shaft.

13. In a lifting mechanism, a hollow standard, a toothed lifting member mounted in said standard for vertical movement, a pinion carried by said standard and adapted to engage the teeth of said lifting member, a worm wheel connected with said pinion, a shaft journaled on said standard, a worm carried by said shaft and meshing with said worm wheel, a second shaft mounted on said standard for axial movement, a gear rigidly secured to said worm shaft, a second gear loosely mounted on said second shaft and having geared connection with the first mentioned gear, a clutch mechanism controlled by the axial movement of said second shaft to connect the same either directly with the first mentioned shaft or with the gear which is loosely mounted on said second shaft.

14. In a lifting mechanism, a hollow standard, a toothed lifting member mounted in said standard for vertical movement, a pinion carried by said standard and adapted to engage the teeth of said lifting member, a worm wheel connected with said pinion, a hollow shaft journaled on said stand-

ard, a worm secured to said shaft and meshing with said worm wheel, a second shaft journaled on said standard and having one end rotatably and slidably mounted in said hollow shaft, a gear rigidly secured to said hollow shaft, a second gear rotatably mounted on said second shaft and having geared connection with the first mentioned gear, said first mentioned gear and said second gear being spaced one from the other, clutch members secured to the adjacent faces of said gears, and a clutch member secured to said second shaft between said gears for movement into operative engagement with either of the first mentioned clutch members.

15. In a lifting mechanism, a hollow standard, a toothed lifting member mounted in said standard for vertical movement, a pinion carried by said standard and adapted to engage the teeth of said lifting member, a worm wheel connected with said pinion, a hollow shaft journaled on said standard, a worm secured to said shaft and meshing with said worm wheel, a second shaft journaled on said standard and having one end rotatably and slidably mounted in said hollow shaft, a gear rigidly secured to said hollow shaft, a second gear rotatably mounted on said second shaft and having geared connection with the first mentioned gear, said first mentioned gear and said second gear being spaced one from the other, clutch members secured to the adjacent faces of said gears, and a clutch member secured to said second shaft between said gears for movement into operative engagement with either of the first mentioned clutch members, and a spring mounted in said hollow shaft and acting on said second shaft to hold the last mentioned clutch member normally in engagement with one of the first mentioned clutch members.

16. In a lifting mechanism, a hollow standard, an outer lifting member mounted in said standard for vertical movement and having teeth on one side thereof, an inner lifting member mounted in said outer lifting member for vertical movement and having teeth on that side thereof opposite the toothed side of the outer lifting member, pinions carried by said standard and arranged to engage the teeth of the respective lifting members, the pinion for the outer lifting member being so arranged that it will be out of engagement with the teeth of that member when the latter is in its lowermost position, means for actuating said pinions whereby one of said pinions will impart movement to said inner lifting member with relation to said outer lifting member, a locking member carried by said outer lifting member and adapted to engage a part of said standard to hold said outer lifting member against vertical movement, an actuating member having one end arranged in operative relation to said lock-

ing member, and means carried by said inner lifting member to engage the other end of said actuating member as said inner lifting member approaches the upper limit of its movement with relation to said outer lifting member and move said locking member to an inoperative position and to impart initial movement to said outer lifting member after said locking member has been moved to its
5 inoperative position.

10 17. In a lifting mechanism, a standard, a toothed member mounted for vertical movement with relation to said standard, a pinion to actuate said lifting member, a shaft operatively connected with said pinion, a second shaft to actuate the first mentioned shaft, said second shaft being mounted for both rotary and axial movement, a variable speed mechanism for connecting said second shaft with
15 said first mentioned shaft and comprising means actuated by the axial movement of said second shaft to control the speed at which said pinion is rotated.

20 25 In testimony whereof, I affix my signature
hereto.

JOHN DOLAN.
